(Cl. 250—27)

This invention relates to electron discharge devices and, more particularly, to a vacuum type electron discharge device and to circuits incorporating the latter.

Vacuum type electron discharge devices are known that may be utilized for amplification, detection, modulation, or oscillation, and the like purposes, one or more of such functions even being realizable in a single device. Other electron discharge devices are known which contain a small amount of gas, space current in which flows upon ionization of the gas and ceases upon deionization of the gas. These latter devices have an off-and-on, blocked and unblocked, operate and non-operate, or "trigger" characteristic. A device which combined the features of the vacuum tube and the gas-filled tube or so-called thyratron, without the limitations of the latter would meet a need in the electron discharge device field.

An object of this invention is to provide a vacuum tube structure that will satisfy this need, and circuit arrangements most simply and efficiently utilizing the characteristics of such a device.

In accordance with the invention, the conventional triode or multigrid vacuum tube is modified to include certain auxiliary electrodes, and to have its anode provided with an aperture to permit a preassigned percentage of the electrons originating at the cathode or filament to pass through. The auxiliary electrodes comprise a deflector member or plate, a secondary electron collecting grid, and a secondary electron emitting anode. The auxiliary anode is positioned out of the straight-line path of particles thrown out by the cathode which would contaminate the secondary electron emitting surface, such particles being collected by the deflector which causes the primary electrons passing through the primary anode's aperture to be deflected and to travel through the collector grid and against the auxiliary anode.

The current-voltage characteristic of the auxiliary anode is such that a zero-current condition exists at a high and at a relatively low potential on that anode. If the latter is at the higher zero-current potential, the external circuit therefor may be disconnected and the anode will "float" at this potential in a stable manner; at the lower zero-current potential, however, the equilibrium is unstable and, if the external circuit is disconnected, the potential falls either way, i. e., the anode returns to a condition of or

near zero potential or rises to the second zero-current potential and is stable therewith.

The modified vacuum tube, i. e., triode, or tetrode or other multigrid tube, in accordance with the invention, will evidence trigger action with substantially no change in the other characteristics of the device as an amplifier, modulator, demodulator or oscillator, as the case may be. The external circuit is such, preferably, that the cathode and the emission anode are connected through a resistance and source of negative potential, the control grid is connected to a point on that resistance and initially biased to beyond primary anode current cut-off, the emission anode is initially at or below the low zero-current potential therefor, and a pulsing circuit is provided for increasing the emission anode's potential to a preassigned extent to raise the control grid to above cut-off, thereby increasing the primary anode current, increasing the secondary emission and causing the auxiliary anode to rise to its high and stable zero-current potential, the control grid having its negative bias further reduced. Alternatively the emission anode may initially be at or above its low zero-current potential, the control grid biased to beyond primary anode current cut-off, and a pulsing circuit be associated with the control grid to reduce the grid bias to above cut-off, the flow of primary electrons causing a rapid rise of the auxiliary anode to its high and stable potential, and the grid being driven even more positive. Obviously, the tube could originally be functioning with input grid control of the primary anode current and variations therein, and a circuit be associated with the control grid or emission anode to trigger-off the tube.

A more complete understanding of this invention will be obtained from the detailed description that follows, taken in conjunction with the appended drawings, wherein:

Fig. 1 shows, in perspective and with portions broken away, an electron discharge device in accordance with this invention;

Fig. 2 is a plan view of the electrode assembly of the device of Fig. 1, taken along the line 2—2 thereof;

Figs. 3 and 3A are plan views, on enlarged scale, of electrode arrangements for the device of Fig. 1;

Figs. 4, 5 and 8 show characteristic curves for a device such as is shown in Fig. 1;

Fig. 6 shows a circuit arrangement, e. g., an amplifying circuit, embodying this invention;

Fig. 7 shows another circuit arrangement embodying the invention;

Figs. 9, 10, 11 and 12 show a pulse counting, an oscillator, a pulse inverting and a multivibrator circuit, respectively, embodying the invention; and

Fig. 13 shows a circuit arrangement embodying the invention, and in which the deflector electrode of the discharge device is utilized as a control electrode.

With reference now to the drawings, the structure of the electron discharge device or vacuum tube in accordance with this invention, will be evident from Figs. 1, 2 and 3.

The discharge device 10 comprises an evacuated envelope or enclosure 11, for example, of glass or other suitable material, having a re-entrant portion 12 terminating in a press 13; and a base 14, which may be of insulating material, and which supports or carries a plurality of contact pins or prongs 15 on which are terminated the external ends of the wires or leads 16, embedded in the portion 12 and adapted for conductive connection to the electrodes of the device.

The electrodes comprise a cathode 17; an inner or input control grid 18; a primary anode 19; a deflector, reflector or guide member, plate or electrode 20; a secondary, auxiliary or collector grid 21; and an auxiliary, secondary electron emitting, or "floating" anode 22. These electrodes are mounted between a pair of spacers or discs 23 of insulating material, for example, mica, spaced apart by supporting rods 24, extensions 25 of which are united to a collar or clamp 26 securely engaging the portion 12. The electrodes are supported in preassigned position, intermediate the discs 23 and relative to each other, by the supporting rods 27, which extend through and make extremely tight fit with apertures or slits in the discs. The getter 33, for flashing in the tube to remove residual gases after the pumping operation, may be mounted on a suitable support 34 depending from one of the extensions 25.

The cathode 17 is of the equipotential type and may comprise a cylindrical metallic sleeve, specifically, nickel with an outer surface of barium and strontium oxide constituting a source of primary electrons when the cathode is heated. The metallic sleeve is fastened onto a cylindrical quartz tube that extends beyond the ends of the sleeve; a heater wire, for example, of tungsten, the ends 28 of which are to be seen in Fig. 1, for indirectly heating the cathode, is threaded through this tube and connected at its ends to a pair of the leads 16. The cathode is connected to the heater wire by a short connection 29. Of course, a filamentary type cathode could be used.

The input control grid 18 surrounds and is coaxial with and spaced from the cathode, and comprises a pair of axially extending frame members on which a large number of turns of closely spaced, fine wire is securely wound.

The primary anode 19 comprises a metallic cylinder, for example, of nickel, and open at each end, that surrounds and is spaced from the grid and is coaxial with the latter and with the cathode. The anode is provided with an aperture or elongated slot 30 that permits a preassigned percentage, for example, ten per centum, of the electrons emitted by the cathode to pass through.

The deflector 20 comprises an arcuately-shaped

metallic sheet, for example, of nickel, spaced from the anode 19 and so disposed with respect to the aperture 30 in the latter that the electrons passing through the aperture are directed toward the deflector, which may be electrically connected through tie-wire 31 to the cathode and, therefore, would be at cathode potential. This deflector causes the electrons that pass out through the aperture 30 to follow trajectories of the character indicated by the dotted lines of Fig. 3, and to pass through the collector grid and to impinge on the secondary electron emitting anode. The secondary electron emission surface of the auxiliary anode is maintained free of contamination by particles from the cathode, because such particles travel in straight lines, and will deposit on the deflector where they can do no harm. Although the deflector is shown connected to the cathode within the envelope 11 it could be brought out to a separate terminal, and, if desired, connected to a source of potential.

The collector grid 21 comprises an elongated, rectangular wire frame member 32 including a plurality of wires 33, spaced apart and arranged in parallel to one another and to the long edges of the frame, and disposed paraxially of the tube and in a plane at a substantial angle—of the order of 30 degrees—to a plane extending at right angles to the spacers and through the electrode assembly along the line A—A of Fig. 2, a paraxial plane through the center of the cathode and the center of the window in the first anode. The collector grid includes a planar metallic or shield portion 36, spaced from the anode 19 and extending substantially at right angles to the rest of the grid and outwardly toward the envelope. In another tube constructed in accordance with this invention, the collector grid comprised a pair of wire supports extending paraxially of the envelope and a plurality of short, parallel, spaced wires extending between the wire supports and at right angles to such supports; and a shield portion similar to portion 36 was provided at each outer edge of the grid, for example, as shown in Fig. 3A.

The auxiliary anode 22 comprises a planar metallic member, for example, of copper, disposed within the angle formed by the collector grid and its shield portion, substantially parallel to the plane of the grid wires. The surface of the anode 22 opposite the collector grid has a good ratio of secondary to primary electrons, for example, a barium-magnesium oxide surface. The surface may be prepared by flashing a barium-magnesium getter button in front of the copper plate in a vacuum. This leaves a clean surface of pure metal. The evacuated enclosure is then opened to air, and the surface immediately oxidizes. The oxidization period preferably is restricted so that only the surface portion of the metallic layer deposited is oxidized. The final layer then comprises a surface portion of magnesium oxide and barium oxide and a sub-layer of magnesium and barium. During operation of the device some of the magnesium and barium may diffuse into the surface portion. The plate is then mounted last, in the tube structure of the device 10. The ratio of metals evaporated is approximately 25 per cent barium and 75 per cent magnesium by weight. With such an auxiliary electrode, it has been found that a secondary to primary electrons ratio of unity is obtainable with primary velocities of only 30 volts or less.

The device 10 may be utilized as an amplifier,

a detector, an oscillator or a modulator. It also has the characteristic that it may be rendered operative or non-operative for such uses substantially instantaneously as the result of applying to or removing a control potential from the auxiliary anode, or the input control grid. In this latter respect, the device is similar to the so-called gas-filled tube without the limitations of the latter. With a gas-filled tube, ionization of the gas must occur before space current is established, and deionization must occur before the space current ceases. One type of gas-filled tube is the hot cathode tube, in which, so long as the input control grid is maintained sufficiently negative with respect to the cathode, ionization will not take place. When the negative bias is decreased sufficiently, however, ionization follows, and, thereupon, the grid loses control over the space current, deionization and cessation of the space current resulting when the anode potential is lowered sufficiently or the cathode-anode circuit is interrupted. In gas-filled tubes, the time required for ionization and for deionization of the gas, the lack of control over the space current, for example, in the case of the hot cathode tube, the noise introduced into the associated circuit by such devices, the changes in the gas content during the life of the devices and their limited application other than in the control or pulsing circuit field, constitute some of the limitations affecting the usefulness of gas-filled tubes.

With the device of this invention, there is no gas to be ionized or deionized, and none of the attendant limitations resulting from its presence. Furthermore, after the device has been rendered operative or "triggered-on," the space current is and remains under control of the input grid until the device is "triggered-off"; that is, the device may be employed in the usual way in which the conventional three-element vacuum tube or triode would be. This is true, also, of the tetrode and pentode or other multigrid tubes, modified to include the deflector electrode, collector grid and secondary anode and the apertured primary anode.

The "trigger" action of the device depends on the floating properties of the auxiliary anode. Fig. 4 shows a family of current versus potential characteristics of this floating anode for a tube constructed in accordance with the invention. The different curves correspond to different potentials on the collector grid. As the potential is increased, the current passes through the zero axis twice. At each of these two points, the number of primary electrons is equal to the number of secondaries which are drawn off the surface. If the floating anode is at the higher zero potential, the external circuit may be entirely disconnected and the element will float in a perfectly stable manner at this voltage. At the lower zero potential, however, the equilibrium is unstable and if the external circuit is disconnected the potential will "fall" either way. If it falls down, the element returns to zero, and, if it falls up, it jumps to the second zero potential and floats stably there.

To understand the reason for this stability, it is only necessary to consider the conditions affecting the addition or removal of charge from the floating anode. Suppose that initially this element is floating at the second zero, and that it starts to drift lower in potential. The voltage difference between it and the collector grid will increase and more secondaries will be drawn away from it. It will, therefore, go more posi-

tive in potential and will thus be brought back to equilibrium. Conversely, if it starts to drift up in voltage, the potential difference between it and the grid will be decreased, and fewer secondaries will be drawn across, thereby decreasing its potential by the accumulation of more negative charge.

Similar reasoning will explain the instability of the first zero, except that, whereas, for the 10 second zero, the number of secondaries which are effective is that drawn off by the potential difference between the collector grid and floating anode, for the first zero, all of the secondaries are drawn across and the true secondary to primary ratio is the important factor. The voltage of the first zero is, therefore, determined primarily by the secondary to primary ratio of the surface of the floating anode, and is thus approximately the same for all values of collector 15 grid potential, but the voltage of the second zero is determined primarily by this potential and the geometry of the collector grid and floating anode 20 structure of the tube.

The curves of Fig. 4 were taken with the first 25 anode current approximately constant at 4 milliamperes. It was adjusted to this value at the start of each curve and changed very little. The first anode was held at the potential of the collector grid. Fig. 5 gives similar characteristics, 30 but with the difference that the control grid potential was held constant at -12 volts for all curves. It indicates the constancy of the first zero potential under different conditions.

If the floating anode is connected to ground 35 through a high resistance, electrons will flow to it from the ground through this resistance because of its positive potential, and these electrons will counteract the effect of an equal number of secondaries simply by replacing the charge carried 40 away by the latter. Now, one effect of reducing the secondary to primary ratio is that the second zero point or stable floating potential is reduced. The floating anode will now float at a potential slightly less than it did when free. This new floating potential is determined by the intersection 45 of the I-V characteristic with the line whose slope is equal to the load resistance. For example, the dotted lines R_1 and R_2 of Fig. 4 have the slopes of one megohm and two-tenths megohm respectively, and the potentials of the points 50 at which they cross the curves are the floating potentials for these resistance values. Resistances smaller than about 1.4×10^5 ohms do not intersect the curves at all, and the critical resistance is therefore near this value. It is given 55 by the formula

$$R_c = \frac{E_m}{I_m}$$

so that, in general, we have that

$$R > \frac{E_m}{I_m} \quad (1)$$

where E_m and I_m are the voltage and current of the negative maximum of the characteristic. The 60 floating anode will not float at values of resistance less than R_c for then the number of electrons supplied via the resistance will be in excess of the number of secondaries needed to maintain the effective secondary to primary ratio at a value equal to unity, and the floating anode will simply charge up negatively and its potential will be brought to zero.

These principles are utilized to get off and on, or operate and non-operate, or block and unblock, or "trigger" action in a vacuum tube.

In the circuit arrangement of Fig. 6, the floating anode 22 is connected through the resistance R and the input grid biasing battery C to the cathode. The input grid 18 is connected to one end of the secondary winding of an input transformer T₁, the other end of the secondary winding being connected to a contact engaging the resistance R and dividing it into two portions R₁ and R₂. The primary anode 19 is connected with the cathode through the primary winding of the output transformer T₂ and the source, for example, a battery B, of anode potential. The deflector 20 is connected to the cathode, and the collector grid 21 is connected to the high potential terminal of the battery B. The values of R₁ and R₂ are such that their total adds up to a value greater than R, preferably considerably greater, one to five megohms being suitable.

Suppose that the cathode heater is turned on, and brought to operating temperature. The floating anode and the inner grid will all be at the negative C potential, and no electrons can flow through the tube. If, now, the potential of the floating anode is momentarily raised to a value greater than the first zero potential (Fig. 4) by application of the necessary potential between terminal A and ground, for example, from the pulsing source S, the potential of the grid will be raised a few volts because of the drop across R₁ and R₂, and a small electron current will flow through the tube. As soon as electrons flow to the floating anode, its potential will jump to the second zero voltage carrying the grid bias up to the operating point. The tube has then triggered-on or "fired," and can be utilized, for example, as an amplifier, through the transformers shown.

It can be triggered-off by decreasing momentarily the potential of the floating anode to a value slightly less than the first zero value, or by sending a negative pulse into the input or grid circuit, i. e., through the transformer T₁, of sufficient value to momentarily cut off the electron flow. The triggering pulses to the floating anode may be applied through a suitable condenser C₁.

Fig. 7 is similar to Fig. 6 with the addition of R₃, and the omission of the pulsing source S and the condenser C₁. R₁, R₂ and R₃ form a bleeder resistance across the total supply battery maintaining the floating anode at a potential slightly in excess of the first zero voltage when no electrons are flowing in the tube. R₁ and R₂ are of such value that, as in Fig. 6, the first grid is held just beyond cut-off when the tube is in the "off" or non-conductive condition. This requires a slightly greater C battery than for the circuit of Fig. 6 since there will be a positive voltage drop through R₂ when the tube is off.

Now if, through the input transformer, a positive potential, for example, of a volt or two, is impressed on the grid, enough electrons (less than a microampere) will be passed to trigger the tube on; the floating anode will jump to the second zero as in the case of the circuit of Fig. 6. The circuit of Fig. 7 thus has an advantage over that of Fig. 6 in that considerably smaller voltages serve to trigger it on. It may be triggered-off by applying a negative signal or pulse in the grid circuit great enough to cut off momentarily the electron stream.

Fig. 8 shows an operating characteristic for the circuit of Fig. 7. A positive potential of 1.2 volts applied between the junction of R₁ and R₂ and the control grid triggers the tube on and

the plate current jumps to point Q on the operating characteristic, or from zero to 7.75 milliamperes. Positive or negative potentials may then be applied, and the plate current will swing up and down as in an ordinary amplifier tube. If a negative potential greater than 10.3 volts is applied, the tube will trigger-off as shown. A comparison of the shape and slope of this curve with those for the triode structure alone, i. e., the cathode, control grid and primary anode, demonstrates that the addition of the trigger mechanism has very little effect on the operating properties of the triode structure.

The value of R₃ may be obtained by calculating the values of R₁ and R₂ as for the circuit of Fig. 6, and then choosing a value for R₃ such that the junction of R₁ and R₃ will have a potential, with no electrons flowing in the tube, slightly greater than that of the first zero of the characteristic (Fig. 4). Obviously, R₃ need not be connected to the highest potential of the power supply.

The tube in the circuit of Fig. 7 is equivalent in most respects to a hot cathode "thyatron." These differences may be noted, however. Since there is no deionization time limitation, the vacuum tube may be made thousands of times faster than the thyatron. The vacuum tube may be "extinguished" or triggered-off by a negative voltage on the grid; while the tube is on, it is not noisy like the gas-filled tube, and its grid maintains complete control over the space current for amplification, oscillation, detection, modulation, etc. The gas tube may be replaced in many of its applications by the device 10, e. g., in pulse counting, oscillator, pulse inverting and relay circuits.

Fig. 9 shows a circuit arrangement for measuring or counting the number of pulses originating in a source S, e. g., for counting the number of alpha particles given off by a radioactive substance. The circuit comprises three counting stages A, B, C, each of which comprises an electron discharge device 10 of the type already described in detail hereinabove.

Each secondary anode is connected to the pulse input terminal through a condenser 90 and the common condenser 91. The collector grid and the primary anode of each tube are connected together and to the high potential terminal of a source 92 of anode potential, which may be common to the tubes 10, a register or counting device or mechanism R being connected between the potential source 92 and the primary anode of stage C. Each cathode is connected to ground, which would permit, if desired, the electrodes of the three devices 10 to be enclosed in a single envelope. Each input control grid is connected through a network 100, comprising a resistance 101 and condenser 102 in parallel and a condenser 103 to a sliding contact 104 engaging the resistance 105 which is connected in series with a condenser 106 between ground and the junction of pulsing input circuit resistance 107 and condenser 91. Each secondary anode is connected through series-connected resistances 108, 109 and network 110, comprising resistance 111 and condenser 112, to the negative terminal of potential source 113 that normally provides a preassigned negative bias on the input grids and normally maintains the emission anode at a potential below its low zero-current potential. Each input grid is connected to resistance 109 through its network 100 and a sliding contact 114 that engages the resistance 108. Each emission

anode, furthermore, is connected through a resistance 105 to the junction of the resistance 109 and network 110 of the succeeding tube which, in the case of the emission anode of stage C, would be resistance 109 and network 110 of stage A.

Initially, the devices 10 are extinguished, i. e., the control grids are biased to beyond primary anode current cut-off and the secondary anode is at a potential below its low zero-current potential. Let it be assumed that it is desired to count the number of impulses or pulses appearing between the input terminal and ground and originating in the source S. The contact 104 is at such a position that that portion of the initial impulse applied to the grid through the condenser 103 and network 100, simultaneously with the application of the pulse to the secondary anode through the condenser 90, causes the grid to rise to a potential above primary anode current cut-off and the rise of the secondary anode to its floating potential, as already outlined heretofore with particular reference to Fig. 6. When the tube of stage A becomes operative or "fires," the tube of stage B is primed so that it will operate or be made conductive by the next pulse applied at the input terminal of the counting circuit. This priming results from the potential built up across the network 110 of the grid circuit of stage B. When the next pulse is received, the tube 10 of stage B becomes operative as did that of stage A and primes the succeeding tube for the succeeding pulse. With tube 10 of stage A on, the pulse that operates the tube of stage B is enough to swing the input grid of stage A positive so that it draws current. This charges condenser 102 so that, after the pulse ceases, the discharge of this condenser through its associated resistance 101 swings the input grid to below primary anode current cut-off and causes the tube of stage A to be extinguished. The next impulse causes the tube of stage C to become conductive, thereby operating the register R to indicate that three pulses have been received, and priming the tube of stage A, the tube of stage B being rendered non-conductive. A fourth pulse causes the tube of stage A to become conductive and that of stage C to become non-conductive. So long as pulses continue to be applied to the circuit's input terminal, the tubes will operate around the ring and the register indicate each time three pulses have been received, or indicate the total number of pulses received at stage C. Of course, registering or indicating mechanism could be associated with each device 10, and any desired number of stages may be used, a three-stage, single register pulse counting circuit being shown by way of illustration. Since the initial position of contact 104 on resistance 105 was to compensate for the absence initially of a priming potential across the resistance 111 of the network 110 in stage A, after the first tube has become conductive, contact 104 may be adjusted to a preassigned position such that until the network 110 does prime the tube of stage A, the pulse succeeding the initial one is not sufficient to render stage A conductive after its extinguishment as a result of the second pulse and operation of stage B.

Fig. 10 shows a relaxation oscillator circuit embodying the invention. It will be observed that the circuit is similar to that of Fig. 7 except that the input transformer T_1 is omitted, the output transformer is replaced by a load resistor R_4 , and

5 a condenser C_{10} is connected between the cathode 17 and the first or primary anode 18.

Let it be assumed that the condenser C_{10} is uncharged, as a result of open switch means (not shown) in the lead between R_4 and battery C and between resistor R_4 and battery B, i. e., when the circuit is not being used. Closure of such switch means would provide the closed circuit shown in condition for oscillation generation, and initiate such oscillations. Current flowing from battery B through resistor R_4 , into the condenser C_{10} charges it and raises the potential of that side of the condenser connected to the primary anode. When, as a result of such potential increase, the anode 18 reaches a sufficiently positive potential, the control grid potential will not be sufficient to prevent the flow of electrons to the primary anode. The flow of electrons starts or "fires" the tube in the manner described with reference to Fig. 7. The grid potential swings from near cut-off to the region of zero potential so that the greatly increased electron flow causes the discharge of condenser C_{10} , effectively bringing both sides of the condenser C_{10} to nearly ground potential once more, and lowering the primary anode potential to a value at which the electron stream is blocked or the tube "extinguished." The process then repeats itself, the condenser being charged slowly and discharged rapidly, resistor R_4 being of such value that the current during the charging period is less than that which flows through the tube to discharge the condenser.

35 The frequency of the oscillations, of a saw-tooth character, is dependent in part, at least, upon the time constant of the circuit defined by the resistor R_4 and condenser C_{10} . Actually, the condenser C_{10} is never fully discharged, but the positive side of it is reduced to a value so low that the primary anode potential is not sufficient to enable electrons to flow through the device 10.

40 A condenser C_{20} may be connected between the control grid 18 and the secondary anode 22, and in parallel with resistance R_1 . This condenser causes the control grid to go positive more rapidly than when it is not added to the circuit, and, hence, enables a higher rate of oscillation to be obtained. The collector grid 21 is shown connected to the primary anode. An alternative arrangement is to connect the collector grid to a high positive potential directly and independently of the primary anode, i. e., the collector grid could be connected directly to the positive terminal of the source B. The potential of the collector grid, in the latter case, does not swing or vary with variations in electron currents.

45 Fig. 11 shows a pulse inverting or inverter circuit embodying the invention. It comprises two discharge devices 10, such as are included in the previously described circuits. The cathodes are connected together and to ground, with the deflector plates connected to the cathodes of their respective tubes. Each primary anode is connected through a load L to the positive terminal of an anode potential source B', the negative terminal of which is connected to ground, and the primary anodes are directly connected through a condenser C_{30} . Each collector grid is connected to its respective primary anode; although it may be connected directly to the potential source B', so that its potential does not swing with variations in the electron currents. The source C' of biasing potential for the control grids is connected between ground and the junction of resistances P_1 , P_2 , the outer ends of which are connected to the secondary anodes. The control

grids are connected to adjustable or slidable contacts S_1 , S_2 engaging with the resistances P_1 , P_2 . The input circuit conductors 50 terminate in an input resistance 60, one end of which is connected to ground and the other through condensers 70, 70' to the secondary anode ends of the resistances P_1 , P_2 . The input terminals 40 may be connected to any suitable source of electrical pulses of positive polarity.

Let it be assumed that the tube D is "fired", i. e., that its secondary anode is at upper zero-current potential, and an electron stream is maintained between the cathode and primary anode; and that the tube E is blocked or "extinguished." Assume, then, that a positive pulse is impressed on the terminals 40, and is of such a value that it elevates the potential of the secondary anode of tube E above its lower zero-current potential. As the secondary anode of tube D is already above that potential, the incoming pulse has little or no effect on the tube D. The control grid of tube E is driven in the positive direction and the tube E is caused to "fire" in the same way as the tube of Fig. 6. As the tube E becomes operative, its primary anode swings negative, and this negative swing is transmitted by the condenser C_{30} to the primary anode of tube D decreasing its potential to such an extent that primary electrons are no longer enabled to flow in tube D, and the latter is extinguished. The next positive pulse received at terminals 40 causes tube D to become operative, and causes tube E to return to its initial inoperative condition. Thus, a series of positive pulses transmitted through the terminals 40 will alternately operate the tubes D, E.

Fig. 12 shows a multivibrator circuit embodying the electron discharge device 10 of this invention. The control grid is connected through a resistance R_5 and source C of biasing potential to the cathode and ground. The cathode is connected to ground and has the deflector plate tied to it. The collector grid and the primary anode are connected together and, through load resistance R_7 , to the high potential terminal of source B of anode potential, the low potential terminal of source B being connected to ground. The secondary or floating anode is connected to an intermediate point on potential source B through a resistance R_6 , and to the control grid through a condenser C_{40} . The collector grid, as in previously described circuits, may be connected directly to the source B of potential so that it does not swing with variations in the electron currents.

The floating anode has a current-voltage characteristic such as is shown in the curves of Fig. 4, and, by virtue of the secondary emission from its surface, its potential increases with increasing primary electron flow to it. This follows, of course, provided that its potential has been raised to a value in excess of the first or lower zero-current potential. Above such a potential, the potential of the floating anode increases positively for positive increases in the magnitude of the primary electron current, and, thus, also, for positive increases in the potential of the control grid. The resistance R_6 couples the secondary anode to the source B to maintain the secondary anode, with no current flowing thereto, at a potential in excess of the low zero-current potential. The resistance R_6 should be of such magnitude that the potential on the control grid varies in response to the impulses it receives through condenser C_{40} from the secondary anode.

If the biasing potential source C is sufficient to maintain the control grid at a potential of a value corresponding to that in the working range of the structure determined primarily by the cathode, control grid and primary anode, there will be certain amount of electrons flowing to the secondary anode, and by virtue of this, its potential will be at a value between the first or lower zero-current potential and the potential of the primary anode and the collector grid. If the potential of the control grid starts to drift in a positive direction, there will be an increase in the amount of electron flow to the secondary anode, and, hence, an increase of its potential in the positive direction. This latter increase is communicated through condenser C_{10} to the control grid to drive it still further in a positive direction to cause a further increase in electron flow to the secondary anode, and a further increase in the control grid's positive potential. This process is regenerative and the potentials of the floating anode and the control grid will swing to the limit in a positive direction. Thereafter, they will start to drift in a reverse direction and by the same process in the reverse sense, the potentials will swing as far negative as possible. This process will be repeated, the frequency of oscillations being determined by the time constants of the circuit elements.

Fig. 13 illustrates another feature of the invention. This circuit is the same as that of Fig. 6, except that the deflector member 20 is connected through the source 80 of adjustable potential to ground, rather than directly to the cathode. With this arrangement, the deflector may be adjusted to a potential different from that of the cathode. For example, after the device 10 has been caused to become conductive in the manner outlined with reference to Fig. 1, the deflector may be adjusted to a negative potential sufficient to prevent enough electrons to reach the anode 22 to enable the latter to remain above its low zero-current potential, whereby the grid potential is reduced to a value below primary anode cut-off, and the device rendered non-conductive or extinguished. Instead of the battery 80, or in addition to it, a circuit element, e. g., a network or an impedance, more specifically, a resistance 81, may be connected between the deflector 20 and ground, or between the battery 80 and the deflector 20, and uni-directional or alternating signal energy applied to the impedance to alter the potential of the deflector with respect to ground and to control the electron current in a preassigned manner.

Although this invention has been disclosed with reference to various specific embodiments, it will be understood that it is not limited thereto, but by the appended claims only.

What is claimed is:

1. In combination, an electron discharge vacuum tube comprising a cathode, an anode, and a control grid intermediate said cathode and anode, an input circuit coupled to said cathode and grid, an output circuit coupled to said cathode and anode, and auxiliary electrodes in said tube, one of said auxiliary electrodes comprising a deflector electrode for deflecting onto another of said auxiliary electrodes primary electrons from the electron stream established between said cathode and anode, said second auxiliary electrode being treated to emit secondary electrons in such ratio as to rise to a floating stable potential, and a circuit connection between said second auxiliary electrode and said grid.

2. In combination, an electron discharge vacuum tube comprising a cathode, an anode and a control grid, an input circuit coupled to said cathode and grid, an output circuit coupled to said cathode and anode, auxiliary electrodes in said tube and including a deflector electrode for deflecting primary electrons onto another of said auxiliary electrodes, said second auxiliary electrode being adapted to emit secondary electrons in ratio greater than unity and having a current-voltage characteristic such that it has zero current at a high and a low potential more positive than said cathode, a connection including a resistance between said second-mentioned auxiliary electrode and said cathode, a connection from said resistance to said grid, means for biasing said grid so that electrons are prevented from flowing to said anode and said second auxiliary electrode and for applying a potential to said second auxiliary electrode of a value between those for zero current, and means to reduce momentarily said grid bias to a value permitting some electron flow to said anode and second auxiliary electrode, whereby the latter rises to its high zero-current potential and the electron flow preventing grid bias is compensated.

3. In combination, an electron discharge device comprising a cathode, an input control grid, a primary anode having a passage therein for a portion of the electrons passing thereto from said cathode, an auxiliary grid, an auxiliary anode and an electron deflecting electrode, said auxiliary anode being an emitter of secondary electrons in ratio greater than unity when bombarded with primary electrons, said deflecting electrode directing onto the auxiliary anode the electrons that pass through the primary anode, an impedance and a source of control grid biasing potential connected in series between said cathode and said auxiliary anode, a connection from said impedance to said control grid, a source of potential connected between said cathode and said primary anode, and an impedance connected between said auxiliary anode and said primary anode potential source.

4. An electrical circuit comprising a vacuum tube having a pair of electrodes between which a stream of primary electrons may be established, an auxiliary electrode having a preassigned floating potential while said electron stream flows, and a control electrode between said pair of electrodes, impedance means connecting said auxiliary electrode and that one of said pair of electrodes with which the electron stream originates, and a connection from said impedance means to said control electrode for biasing it to a potential above that at which the electron stream would be blocked, while said auxiliary electrode is at said preassigned potential.

5. An electron discharge device circuit comprising a vacuum tube having an electrode constituting a source of electrons, a second electrode for receiving said electrons, a third electrode intermediate said first and second electrodes for regulating the electron flow therebetween in accordance with signal variations impressed on said third electrode, a fourth electrode for receiving a preassigned portion of the electrons from said first electrode but located outside of their normal paths, a fifth electrode for deflecting said preassigned portion of electrons from their original paths to said fourth electrode, and means including said fourth electrode for blocking and

15 unblocking the electron stream to said second and fourth electrodes.

6. An electron discharge device circuit comprising a vacuum tube having an electrode constituting a source of electrons, a second electrode for receiving said electrons, a third electrode intermediate said first and second electrodes for regulating the electron flow therebetween in accordance with signal variations impressed on said third electrode, a fourth electrode having a secondary electron emission surface for receiving a preassigned portion of the electrons from said first electrode but located outside of their normal paths, a fifth electrode for deflecting said preassigned portion of electrons from their original paths to said fourth electrode, a sixth electrode constituting a secondary electron collecting electrode, and means including said fourth electrode for blocking and unblocking the electron stream to said second and fourth electrodes.

7. An electron discharge device circuit comprising a vacuum tube having an electrode constituting a source of electrons, a second electrode for receiving said electrons, a third electrode intermediate said first and second electrodes for regulating the electron flow therebetween in accordance with signal variations impressed on said third electrode, a fourth electrode for receiving a preassigned portion of the electrons from said first electrode but located outside of their normal paths, a fifth electrode for deflecting said preassigned portion of electrons from their original paths to said fourth electrode, and means including said deflecting electrode for blocking and unblocking the electron stream to said second and fourth electrodes.

8. An electron discharge device circuit comprising a vacuum tube having an electrode constituting a source of primary electrons, a second electrode for receiving said electrons and having a passage therein so that a preassigned portion of said electrons may pass through, a control electrode between said electrodes for regulating the flow of electrons therebetween in accordance with signal variations impressed on said control electrode, a secondary emission electrode for receiving said preassigned portion of said electrons, a secondary electron collecting electrode, a deflecting electrode for deflecting said preassigned portion of electrons onto said emission electrode, means for connecting said emission and control electrodes and for placing a preassigned biasing potential on said control electrode, means for maintaining said collecting electrode and said second electrode at preassigned potentials, and means for altering the potentials on said control and emission electrodes so that the control electrode is at a potential that does not block electron flow to said second electrode.

60 9. An electrical circuit comprising an electron discharge device having a pair of electrodes between which a stream of primary electrons may be established, an auxiliary electrode constituting a source of secondary electrons and activated by some of the primary electrons, an electrode for deflecting said primary electrons onto said auxiliary electrode, and means for impressing a potential on said deflecting electrode to block passage of primary electrons to said auxiliary electrode.

10. The combination of a source of electrical pulses and a circuit for counting the number of pulses originating in said source, said circuit comprising a plurality of vacuum electron discharge devices connected in tandem, each of said

devices comprising a pair of electrodes between which an electron stream may be established, a control electrode between said pair of electrodes, a secondary electron emission electrode, means for establishing electron streams successively in said devices upon successive pulses, and means in the control electrode circuit of each device for causing the control grid to block the electron stream in the particular device as a result of said control electrode drawing current on the pulse succeeding that which established the electron stream in the particular device.

11. An electric discharge vacuum tube comprising a cathode, an anode for receiving primary electrons from said cathode, an auxiliary anode positioned to be bombarded by some of said primary electrons, and adapted to emit secondary electrons in ratio greater than unity whereby said auxiliary electrode rises to and floats at a stable potential, and a grid biased negatively with respect to said cathode and positioned in the stream of electrons bombarding said auxiliary anode, and means connecting said floating anode and said grid.

12. In combination, an electric discharge vacuum tube comprising a cathode, an anode for receiving primary electrons from said cathode, an auxiliary anode positioned to be bombarded by some of said primary electrons and adapted to emit secondary electrons in ratio greater than unity whereby said auxiliary anode rises to and floats at a stable potential, and a grid biased negatively with respect to said cathode and positioned in the stream of electrons bombarding said auxiliary anode, and means providing a direct resistive connection between said floating anode and said grid.

13. In combination, an electric discharge vacuum tube comprising a cathode, an anode for receiving primary electrons from said cathode, a control grid between said cathode and anode, and an auxiliary anode positioned so as to be bombarded by a portion of said electrons when electron flow occurs between said cathode and said first anode, said auxiliary anode being adapted to emit secondary electrons in ratio greater than unity, means for biasing said grid to a potential such as to block electron flow between said cathode and anode, means connecting said grid and said auxiliary anode, and means connected to said grid and said auxiliary anode for momentarily reducing the grid bias so that electrons flow to said auxiliary anode whereby secondary electron emission by said auxiliary electrode raises the latter to a floating stable potential thereby maintaining the bias on said grid above electron blocking potential until the potential on said grid is momentarily reduced to a value blocking electron flow between said cathode and first anode.

14. In combination, a source of electrical pulses and a circuit for indicating the number of pulses originating in said source, said circuit comprising a plurality of interconnected vacuum electron discharge devices, each of said devices comprising a pair of electrodes between which an electron stream may be established and a secondary electron emission electrode, means responsive to one of said pulses and connected with one of said pair of electrodes and with said secondary electrode of one of said devices for estab-

lishing primary and secondary electron streams in said one device and for priming a second of said devices for later establishment of similar electron streams in said second device, and means responsive to a second of said pulses to establish said electron streams in said second device and to disestablish the electron streams in said first-mentioned device.

15. In combination, a plurality of interconnected vacuum electron discharge devices, each of said devices including a pair of electrodes between which an electron stream may be established and a secondary electron emission of electrode, means connected to one of said pair of electrodes of one of said devices for establishing secondary electron emission in said device and for priming a second of said devices for establishment of secondary electron emission in said second device, and means for establishing secondary electron emission in said second device and for disestablishing the secondary electron emission in said first-mentioned device.

16. In combination, a plurality of interconnected vacuum electron discharge devices, each of said devices including a pair of electrodes between which an electron stream may be established and a secondary electron emission electrode, means connected to one of said pair of electrodes of one of said devices for establishing secondary electron emission in said device and for priming a second of said devices for establishment of secondary electron emission in said second device, and means for establishing secondary electron emission in said second device and for simultaneously disestablishing the secondary electron emission in said first-mentioned device.

17. In combination, a plurality of interconnected vacuum electron discharge devices, each of said devices including a pair of electrodes between which an electron stream may be established and a secondary electron emission electrode, means connected to one of said pair of electrodes of one of said devices and to the secondary electron emission electrode of said one device for establishing secondary electron emission in said device and for priming a second of said devices for establishment of secondary electron emission in said second device, and means for establishing secondary electron emission in said second device and for disestablishing the secondary electron emission in said first-mentioned device.

18. In combination, a plurality of interconnected vacuum electron discharge devices, each of said devices including a pair of electrodes between which an electron stream may be established and a secondary electron emission electrode, means connected to one of said pair of electrodes of one of said devices for establishing secondary electron emission in said device and for priming a second of said devices for establishment of secondary electron emission in said second device, and means for simultaneously establishing secondary electron emission in said second device, for indicating the establishment of secondary electron emission in said second device, and for disestablishing the secondary electron emission in said first-mentioned device.
